APPARATUS FOR SURFACING OF BOTH
FACES OF A RIBBON OF GLASSEdmond Laverdissé, Auvelais, Belgium, assignor
to Les Glaceries de la Sambre, Société Ano-
nyme, Auvelais, Belgium, a Belgian company

Application May 14, 1952, Serial No. 287,683

Claims priority, application Belgium May 16, 1951

12 Claims. (Cl. 51—56)

1

The present invention concerns the simultaneous surfacing (i. e. grinding and/or polishing) of the two faces of a continuous ribbon of glass by means of tools in the form of rotating discs which are mounted on supports or beams disposed transversely in relation to the ribbon of glass.

The invention has for its principal object to facilitate the operations which must be performed for the purpose of cleaning, inspecting and adjusting the tools, and has the further object of providing improvements in the arrangement and mounting of the beams.

According to the invention, the removal of the surfacing tools for the purpose of maintenance is effected by successively imparting to a tool-supporting beam as a whole vertical movement from its operative position and a lateral movement to the inspection and/or cleaning station. For this purpose, each tool-supporting beam extends transversely above a horizontal running path or track and is detachably engaged by its ends to supports situated in a plane perpendicular to the sheet of glass so as to permit, by relative movements carried out in this plane, the disengagement and vertical displacement of any lower beam from its working position towards the level of the running path or track. It is thus possible to remove or return into position, as a whole, the working tools and the beam 30 on which they are mounted and thus to impart to the latter the freedom of movement necessary to enable it to be brought to the inspection or cleaning stations without interrupting or impeding the operation of the adjacent beams. The supports of the beams may be so mounted as to be able to carry out vertical or horizontal movements. In the first case, they are maintained in the working position by locking devices and their vertical movements are controlled by hy- 40

draulic, mechanical or electric hoisting devices supported by frames consisting of the posts of a framework supporting the installation.

When the beams must be adapted to be re-

ciprocated across the glass, they rest on car-

riages which in turn move horizontally on the vertically movable supports.

The tool-supporting beams and the carriages or supports thereof are provided with engage-

50

ment members which interengage when a beam

is laid on the carriages or supports, but are automatically disengaged when the beam is raised from the latter. The beam thus becomes an interchangeable member and can be immediately replaced by another beam.

In the accompanying drawings, which illustrate diagrammatically by way of example installations according to the invention:

Figure 1 is an elevational side view, partly in section on the line I—I of Figure 3, of an installation with running tracks.

Figure 2 is a cross-section on the line II—II of Figure 1.

Figure 3 is a plan view, partly in section on the line III—III of Figure 1.

Figures 4 to 6 are detail views showing the device for locking the beams.

Figure 7 shows in elevation a device for actuating and coupling the beams of one pair.

Figures 8 and 9 are front and side elevations respectively, of tool-supporting beams resting on supports laterally movable in the frames.

Figures 10 and 11 show in vertical section on the line X—X and in horizontal section on the line XI—XI respectively, beams resting on fixed supports.

Figures 12 and 13 are diagrammatic views in elevation and in plan respectively, showing a complete installation.

The continuous ribbon of glass 1, leaving an annealing furnace is conveyed in known manner on horizontal rollers 2 successively through a grinding apparatus and through a polishing apparatus. Apart from the glass-working tools, which consist of metal discs (irons) for the grinding, and of discs lined with felt (pads) for the polishing, the arrangement and the operation of these apparatus are identical; and only one of them has been shown in the drawings for the sake of simplicity.

The upper working tools 3 and the lower working tools 3', actuated with a rotational movement, are supported by beams 4, 5 arranged in pairs, one above and the other below the glass 1, so as to work the two faces thereof simultaneously. Each pair of beams is actuated with a reciprocating movement transversely in relation to the ribbon of glass and is supported in frames or a framework constituting vertical slideways 6 for the supports of the beams.

3

Each lower beam 5 rests at its ends on carriage 7, the carrying rollers 8 of which travel along horizontal tracks 9 mounted on supports 10 connected to plates 11 supported by the rods of hydraulic pistons 12 adapted to slide in cylinders 13.

In the working position, that is to say, in their upper position determined by stops 15 (Figure 1), the beams 5 are maintained at the required height by locking devices 14 (Figure 4) which secure the plates 11 of the supports 10 in position when they have been brought against the stops 15 by the hydraulic pressure exerted below the pistons 12. For this purpose, use may be made of a control device comprising a main duct 16 for fluid under pressure, and for each beam 5 a branch 17 with a distributor 18 for the control of the pistons 12, and branches 19, 39 with a distributor 20 for the control of the locking devices 14 (Figure 4).

The distributor 18 comprises a rod 21 (Figure 5) which, actuated by a hand lever 22, slides in a sleeve 23 having ports 24 formed therein. When the hand lever 22 is lowered, the fluid admitted at 25 through the gate valve 26 passes through the grooves 27 and arrives through 28 in the branch 17, through which it is admitted into the cylinders 13 so as to lift the pistons 12. When the hand lever 22 is placed in the upper position (indicated by a dash-dotted line), the passage of the fluid through the grooves 27 is interrupted and the valve 29, at the lower end of the rod 21, places the duct 17 in communication with the discharge pipe 30.

The distributor 20 comprises a rod 31 provided with pistons 32 and controlled by the hand lever 33. When the latter is in its lower position (Figure 6), the fluid under pressure admitted at 34 through the valve 35, enters the branch 19, by which it is conducted to the small cylinder 36 behind the piston 37 connected to the locking device 14, which is adapted to engage in a catch 38 provided in the plate 11, while the liquid situated in front of the piston 37 escapes through the discharge ducts 39, 40. When the hand lever 33 is raised (position shown by a dash-dotted line), the liquid coming from 34 is sent through the duct 39 in front of the piston 37, which disengages the locking device 14 and releases the plate 11, while the liquid which was situated behind the piston 37 is forced through the branch 19 and the discharge duct 41.

The hand levers 22 and 33 are operated when it is desired to withdraw a beam 5 for the purpose of cleaning or replacing it, these operations taking place without interrupting the advance of the sheet of glass. At the end of its downward movement, the beam 5 rests on a transporter constituted, for example (Figure 1), by series of rollers 42. The carriages 7 continue their downward movement until the plates 11 of the supports 10 rest on the cylinders 13. In order to facilitate the engagement and disengagement of the beams 5 by the carriages 7, they are provided respectively with engagement projections and recesses of conical form 43 (Figures 2 and 7).

In the arrangement illustrated, the rollers 42 turn freely on their spindles and the beams 5 mounted thereon are carried along by the engagement of a dog 45 with a tooth 45' connected to a chain 44 controlled by a suitable motor, towards the inspection and cleaning station. A replacement beam is then brought above the supports 10, which are then raised and secured in position by the locking devices 14.

4

The upper beams 4 are supported, similarly to the beams 5, at their ends by carriages 47 travelling on rails 59 suspended on supports 46 secured to the piston rods 48 moving in the cylinders 49.

5 The working position of the upper beam lies at the lower end of its travel, the supports 46 then resting on the cylinders 49 so that no locking is necessary.

In order to reach the inspection and adjustment position, the beam 4 is raised above the rollers 59 by the admission of fluid under pressure into the cylinders 49 through the gate valve 51 (Figure 4) and the duct 52 controlled by the distributor 53 similar to the distributor 18 hereinbefore described. The rollers 59 intended to receive the beam 4 must be adapted to be retracted in order to permit the passage of the beam. For this purpose they are mounted, for example, on sliding arms or, as shown, on pivoting arms 54 (Figure 3), which return them into position as the beam passes. The latter, the travel of which is limited in the upward direction by stops 55, is then laid on the rollers 50 and moved by the engagement of a dog 56 with the tooth 56' secured to the endless chain 57. The reverse operation permits of returning a beam into the working position.

Instead of being laid directly on the rollers 42 and 50, the beams 5 and 4 can obviously be laid on transporter frames such as that illustrated at 58 (Figure 1), in order to facilitate their subsequent conveyance, if required, in directions perpendicular to the planes of rotation. Other conveying means, such as travelling platforms, could obviously be substituted for those hereinbefore more particularly described.

It is to be noted that, instead of the two beams of each pair, only the lower beam or the upper beam may be mounted in the slideways 6.

40 In the working position, the beams 4 and 5 are moved transversely to the glass sheet by reciprocating movements imparted to the carriages 7 and 47, either together or in opposite directions to one another. In the installation illustrated in Figures 1 to 3, one of the supports 10 carries a motor 60 (Figure 7) which, through the reduction gear 61 and the connecting rod 62, imparts a reciprocating movement to the carriage 7 and consequently to the beam 5. The beam 4 is caused to follow this movement of the beam 5 by a stud 63 having a conical head which is secured to the carriage 7 and engages in a recess of corresponding form in the support 46 when the two coupled beams are in the working position.

55 The working tools 3, 3' (irons for the grinding and polishers for the polishing) mounted on the beams 4 and 5 respectively are preferably synchronously rotated by means of the motor 64 mounted on the beam 4, the said motor actuating both the shaft controlling the upper tools 3 and the shaft 66 which, through a coupling 67, 68 and a shaft 69, drives the shaft 70 controlling the lower tools 3'. The coupling 67, 68 is, for example, of the dog or friction type so that it is automatically engaged and disengaged when the beams 4, 5 are placed in position and removed respectively. This arrangement permits of employing tools of non-circular form maintaining those of one beam exactly opposite those of the beam cooperating therewith.

60 In the construction illustrated in Figures 8 and 9, the beams 4 and 5 rest on supports designated by 81 and 82 respectively, which are mounted on rollers. The upper beam 4 is provided with rings 75 83 to enable them to be gripped by means of

hooks suspended, for example, from a crab (not shown). The lower beam 5 is adapted to be moved by means of jacks 84 mounted on a transporter 85 which, in the example in question, is in turn mounted on a travelling platform 86 travelling on a track 87 extending parallel to the glass sheet 1.

In order to permit disengagement of the beam 5, the supports 82 are made laterally movable and can be moved on rails 88 under the control of pistons 89 mounted in hydraulic cylinders 90. The rails 88 rest on brackets 91 secured to the frame 92. The distance between the brackets 91 is greater than the width of the beam, so that when the supports 82 have been retracted the beam can pass freely between the brackets.

In order to disengage the beam 5 from its working position, the transporter 85 is placed in position, and when the tools 3' have been lowered, the beam is lifted slightly by means of the jacks 84 in order to disengage the engagement projections 93 on the supports 82. The latter having been laterally retracted, the beam is lowered by the jacks into the position 5' illustrated in chain lines, and it can then be conveyed to the inspection station and subjected to the necessary cleaning or repairs.

The supports for the lower beam may also be fixed provided that relative movement of the beam for the disengagement thereof is allowed for. In the construction illustrated in Figures 10 and 11, the beam 5 is provided with the lateral bearing lugs 94 which rest on brackets 95 secured to the frame 92.

In order to produce the disengaging movement, a transporter 96 is employed, the jack 97 of which supports a platform 98 provided with supporting rollers 99. When the tools 3' have been lowered, the jack raises the platform 98 until the beam 5 is disengaged at 100 from the brackets 95, whereafter the beam 5 is laterally moved by means of the rollers 99 in order to disengage the lugs 94 from the brackets 95, the jack is lowered and the beam is pushed into the central position illustrated at 5' in Figure 10.

The jacks illustrated in Figure 8 are of the screw-and-nut type and that illustrated in Figure 10 is of the telescopic hydraulic type, but it will be understood that any other known type of jack could be employed, the features of the invention residing, not in the construction of the hoisting means, but in the arrangement of the beams above a rolling path or track and opposite supports permitting vertical movement of the beams from their working positions without interrupting the operation of the installation.

A complete installation according to the invention is illustrated diagrammatically, on a much reduced scale, in Figures 12 and 13, in which F designates the glass-melting furnace, E the lehr or annealing furnace, B the frames of the grinding and/or polishing machine and P and P' the maintenance stations which are assumed to be situated at different levels, but which may also be situated at the lower level, either in alignment with the frames B or laterally as indicated in Figure 13.

I claim:

1. Apparatus for the surfacing of the two faces of a ribbon of glass, comprising tool carrying beams extending transversely of said ribbon of glass, a service station and means for imparting successively to any of said tool-carrying beams a vertical movement from their working position in which said beams are stationary in

the longitudinal direction of the glass ribbon to a position vertically spaced from said stationary working position, and a horizontal movement from said vertically spaced position to said service station.

2. Apparatus for the surfacing of both faces of a continuous ribbon of glass comprising a series of pairs of parallel tool-carrying beams extending transversely of said ribbon of glass, each pair comprising an upper beam and a lower beam, a horizontal track extending under said ribbon of glass, pairs of supports for said beams situated in planes at right angles to said track, said supports and beams being capable of relative movements in said planes while remaining stationary in the longitudinal direction of said track, means for vertically moving said beams in said planes and means for horizontally moving said lower beams along said track.

3. Apparatus for the surfacing of both faces of a continuous ribbon of glass comprising means for supporting said ribbon of glass along a predetermined horizontal path, vertical frames on both sides of said path, a series of parallel tool-carrying upper and lower beams extending transversely of said path, vertical guideways in said frames, pairs of supports slideable in said guideways, each of said beams resting on a pair of supports, a horizontal track below and parallel to said path, means for moving any lower beam with its supports along its guideways from its working position to the level of said track and vice-versa, and means for moving any lower beam along said track.

35. 4. Apparatus as claimed in claim 3, comprising an upper horizontal track above and parallel to said path, means for moving any upper beam with its supports along its guideways from its working position to the level of said upper track and vice-versa, and means for moving any upper beam along said upper track.

5. Apparatus as claimed in claim 3, wherein the supports for the lower beams are retractable to permit lateral disengagement of the beams supported thereby.

6. Apparatus as claimed in claim 3, comprising reciprocating carriages interposed between the said lower beams and their supports, and means for reciprocating said carriages.

50. 7. Apparatus as claimed in claim 3, comprising means for locking the supports for the lower beams in position, when said lower beams are in their working position with respect to the ribbon of glass.

55. 8. Apparatus as claimed in claim 2, comprising a transporter on said track, said vertically moving means being mounted on said transporter.

9. Apparatus as claimed in claim 8, wherein the beams are supported at their ends on said supports by means of interengaging members such that the beams are released from their supports, when, in the course of the downward movement of the latter, the beams rest on their respective transporters.

65. 10. Apparatus as claimed in claim 3, comprising an upper transporter for receiving said upper beams, means for vertically moving any of said upper beams from its working position to said upper transporter and vice versa, and retractable elements allowing passage of said upper beam during its vertical movements.

70. 11. Apparatus as claimed in claim 3, wherein the support of only one of the beams of a pair of tool-supporting beams is provided with a reciprocating device, and that the carriages of

the two beams support interengaging members such that they come into engagement when the said beams occupy their working positions.

12. Apparatus as claimed in claim 3, wherein one of the beams of one pair is provided with a motor to actuate the tools, and that each beam is provided with a horizontal shaft for the transmission of the movement to the tools and with a vertical shaft on which a coupling member is mounted, the arrangement of the coupling members being such that they interengage when the two co-operating beams occupy their working positions.
